CONVERSION OF PETROLEUM OILS

William Alvah Smith, Hamburg, N. Y.

Application January 13, 1942, Serial No. 426,602

12 Claims. (Cl. 196—55)

This invention relates to the conversion, by controlled heat treatment, of petroleum oils into refined components with superior physical characteristics, which refined components may be separated according to their different boiling temperatures.

This invention is an improvement upon, and continuation in part of, my prior copending application Ser. No. 302,927, filed November 4, 1939.

One object of the invention is to improve the conversion of petroleum oils. Another object of the invention is to provide an improved method of controlled conversion and/or cracking of hydrocarbons, such as petroleum oil, which may be carried out by relatively simple and inexpensive apparatus, with which the overhead products obtained will have improved viscosity index, improved physical characteristics, with which one may obtain if desired a maximum possible proportion of light bodied lubricants of high quality, and a minimum proportion of less desirable heavy bodied oils, and which will be relatively simple, practical and efficient.

Other objects and advantages will appear from the following description of some practical applications of the invention, and the novel features will be particularly pointed out hereinafter in connection with the appended claims.

Under the proper temperature and contact time relationships, lubricating oil bases are selectively cracked and rearranged to yield lubricating oils having more desirable physical properties. This is effected according to this invention, by subjecting the lubricating oil bases to reaction with acid activated clays under the proper temperatures and contact time conditions. Where the lubricating oil base contains deactivating components, such, for example, as sulphur, certain metallic compounds in small quantities are useful for neutralizing the deactivating properties of the undesirable components, and thereby substantially increase the activity of the acid activated clay.

The acid activated clay permits degradation and separation of undesirable fractions and an

improvement, rather than the degradation that would be expected from the temperature relationships, of the more desirable portions of the oil. It is well known that all lubricants become less fluid as temperatures decrease. A high viscosity index oil is one whose fluidity changes relatively less with a given temperature change, which for example, will permit easier starting of a cold engine having such an oil in its crank case or bearings, because of the lower internal friction of the oil itself. Additives have been developed to improve, or raise the viscosity index but such materials in the quantities specified, according to some literature published in connection with such a commercial additive, had substantially no effect on flash, pour, carbon, color, or other physical characteristics of the oil.

Additives of this type are usually added to the oils which initially have been improved by selective solvent extraction of the more desirable components, and to eliminate as large a proportion as possible of that portion having the undesired characteristics, but no improvement in the physical characteristics of the selected components is achieved by solvent extraction. On the contrary, actual physical improvement of the useful parts of the oil is achieved by the control of treatment permitted by the proper application of acid activated clay, either alone or in connection with proper amounts of auxiliary agents in finely divided form, such as metallic oxides or other chemicals of which copper oxide and aluminum oxide are common examples; the particular auxiliary agent is selected in accordance with the requirements of the material itself, so that entirely new substances with markedly improved physical characteristics are obtained, with more or less complete elimination of undesirable or unstable compounds. Improvement in oils from naphthenic sources, both solvanted and non-solvanted, is effected by this means.

In connection with the production of large quantities of the light bodied lubricants of high quality, it is well known that crude oils seldom contain lubricating components in the desired relationship to marketability. For example, Penn-

sylvania crude oil contains roughly twice as much heavy residual lubricating oil as it does of the so-called neutral or volatile lubricating component, yet the normal market demand from automobile and truck trade is for relatively light bodied lubricants containing a high proportion of light lubricating oil. At times the demand for heavy Pennsylvania residual oil is so small as to make the value of this oil to the refiner only slightly higher than that of fuel oil from much cheaper crudes, resulting in loss of revenue both to the refiner and the crude oil producer.

According to this invention the conversion and/or cracking of petroleum oils, and particularly the heavy bodied oils, can be effectively controlled and greater yield of the desirable components such as light bodied oils, obtained by performing the conversion and/or cracking in the presence of acid activated clay. The clay is, of course, in finely divided form and preferably fresh or unspent, or reactivated. It is mixed with the oil to be converted preferably while the latter is well below the natural cracking temperature of that oil, such as below 400° F., and where an auxiliary agent in finely divided form is employed, it can be mixed with the clay and the mixture dispersed throughout the oil before the oil reaches the cracking temperature. The oil plus clay mixture is then subjected to cracking or conversion conditions and temperature. It is important for best results that the oil be in intimate contact with the acid activated clay before the conversion starts. If the oil is heated approximately to the conversion or cracking temperature before being brought in contact with the clay, or there is no intimate mixture of the clay and the oil, the clay may be unable to effect satisfactory and complete control of the conversion, with the result that too much of the wrong fractions or components is produced and not enough of the more desirable components, such as the light bodied lubricants. The cracking or conversion temperature to which the base oil is heated will depend on various factors, such as the source and character of the oil and the nature of the catalyst employed, which factors are well understood in this industry. By way of example, in the apparatus shown, temperatures of 800° F. to 890° F. in the transfer line and of 565° F. to 740° F. in the base of tower section 1 were employed to produce satisfactory results in treating Pennsylvania 600 S. R. oil.

Different oils require variations as to treatment, such as for example, quantities of activated clay, chemical modifiers, temperatures, time of reaction, and desired end results. Such variables must be determined experimentally. To enable those experienced in the art readily to apply the invention without undue experimentation, the data elsewhere herein concerning results obtained from the treatment of dewaxed Pennsylvania 600 steam refined stock are indicative.

In the accompanying drawing, the single figure is a schematic diagram of a simple system for performing this invention, which has been successfully operated.

In the drawing, the heavy bodied oil or crude oil to be treated is mixed with the acid-activated clay and placed in a tank or reservoir 10, and if an auxiliary agent is to be employed, it may also be mixed in finely divided form with the clay and the oil, so that the agent and the clay will be dispersed as much as possible throughout or suspended in, the oil to produce a pumpable mixture.

The mixture of the oil with the clay and agent dispersed therethrough is withdrawn from the tank 10 through a conduit 11, controlled by a valve or gate 12, by means of a pump 13, and this pump delivers a stream of this mixture through conduit 14 to the lower end of a heating coil 15, which coil passes upwardly through a heating chamber 16. The upper end of the coil 15 is connected by a conduit or pipe 17 also called a transfer line, to the upper end of a reaction or flash chamber 18 which is disposed vertically in a heating chamber 19 that communicates with the heating chamber 16 by an aperture 20 in a partition 21 which divides the chambers 16 and 19 from one another. Hot gases are supplied to the lower end of the chamber 16 in any suitable manner, such as through a pipe or conduit 22 and after rising in the chamber 16, they pass through opening 20 in partition 21 to the upper end of the chamber 19, and then the gases descend to an outlet flue pipe or conduit 23 leading to the smokestack. The distribution of gas travel is controlled by damper 24 in conduit 23, by valve 24a controlling opening 20; and valve 40 in pipe 39.

The showing of the direction of movement of the heating gases relatively to the oil and clay mixture is merely schematic, and actually their relative direction of movement will be largely opposite to one another according to counter-flow principles and good engineering design to secure the most efficient heat exchange.

The bottom of the reaction or flash chamber 18 is provided with an outlet pipe 25 controlled by valve 26 through which the bottoms and suspended clay and any auxiliary agent, that is, the heavy residual oil in which the clay and agent are carried, are removed. These bottoms with clay are removed to any suitable reservoir for subsequent treatment to remove the clay and agent and to utilize the oil component of the mixture.

Frequently steam or vacuum can be used to facilitate the removal of volatile products, or lighter petroleum fractions can be used, particularly where a change in the character of the lighter fractions is desired. Recycling of lighter petroleum fractions enables the treatment on these fractions to be carried to any desired point, in spite of the fact that their vaporization characteristics might otherwise limit the feasible time and temperature relationship. In this way, long continued treatment of even gasoline fractions at temperatures of 500° F. or higher is possible, and the desired molecular changes achieved.

In this particular apparatus, as shown, steam under pressure may be admitted through pipe 27 into the lower end of the reaction or flash chamber 18, and the steam arising through this chamber not only aids the reaction but is of assistance in carrying off the lighter fractions or components into fractionating tower 28 having sections designated 1, 2, 3, and 4. In application of the process, a greater or less number of sections may be employed, as conditions may require. This fractionating tower may be separate from the reaction or flash chamber, but connected at its lower end to the upper end of the flash chamber. This connection is most easily accomplished by superposing the two in the form of one unitary structure as shown diagrammatically in the drawing.

Outlets A, B and C are provided at intervals along the height of the fractionating tower for removing the overhead products of different boiling temperatures, that is, different components

with different boiling ranges, and each outlet passes through a cooler 29. These reaction or flash chambers 18 and fractionating towers 28 with a number of overhead outlets such as A, B, and C are well known in the industry, and for that reason, have been shown only diagrammatically. From the top of the fractionating tower 28, the most volatile components are removed through a conduit 30 and then conveyed to the upper end of a condenser coil 31, which in turn discharges at its lower end 32 into a suitable reservoir 33. A cooling medium is circulated upwardly around the condenser coil 31 in a cabinet 34, the cooling medium being conducted into the cabinet 34 by a pipe 35 and removed by a pipe 36 open-

branch pipes 47, 48 and 49, controlled respectively by valves 50, 51 and 52, to the upper ends of sections 1, 2 and 3 of the tower 28 so that vapors from different tower sections may be carried directly to the pipe 30 and thus by-passed directly to the condenser coil 31.

Examples of results that can be achieved in accordance with this invention by the application of one pound of acid-activated clay to each gallon 10 of heavy oil to control the alteration of dewaxed "Pennsylvania 600 S. R. stock" to produce relatively large amounts of high grade "S. A. E. 20" motor oil and high grade Bright stock, are set forth in the table below, which tabulates the results of three tests:

	Orig. oil dewaxed Penns. "600 S. R. stock"	Test 110		Test 111		Test 112

ing out of the upper part of the cabinet. The temperature to which the oil is heated in the coil 15 and in the reaction chamber 18 will depend upon the many factors well understood in the art, one of which is the character of the cracking agent, if one is employed. For example, some agents cause cracking at lower temperatures than others.

The flashing action may also be aided by introducing suitable amounts of water, or more highly volatile hydrocarbons such as gasoline and lighter fractions, into the mixture of oil and finely divided clay and agent, before the oil and clay enter the heating coil 15. For example, the water or gasoline may be introduced through a pipe 37 controlled by valve 38 into the pipe 14, and as this new mixture is heated in the coil 15, the water or highly volatile hydrocarbon will be heated to the vaporizing stage, and then when they reach the chamber 18 the water or gasoline will pass off through the tower and carry some of the lighter components with them. The action in this respect is similar to that caused by the introduction of steam through the pipe 27, and, may replace or supplement the action caused by the steam admitted through pipe 27. It may also be desirable, at times, to separately control the temperatures in the chambers 16 and 19 and for that purpose the chamber 16 may have a direct outlet 39 at its top controlled by a valve 40, so that some of the gases from the chamber 16 may escape directly instead of passing through the chamber 19.

A heating medium such as a hot gas may be admitted to chamber 19 through a pipe 41 controlled by a valve 42. The pipe 30 at the top of the tower 28 is provided with a control valve 43, and at a point between the valve 43 and the condenser coil 31 is connected by a pipe 44 to the transfer line 17. The line 17 at a point between its connection to the pipe 44 and the chamber 18, is provided with a controlling valve 45, and the pipe 44 is provided with a controlling valve 46. The pipe 44 in the zone between the valve 46 and the connection to the pipe 30 is connected by

Test #110 also yielded 4% of kerosene, 8% of gas oil, a loss of 1.3%, 2% of 63.5 sec. viscosity 2 plus color "nonvis neutral" and 8% of #2 color "180 neutral"; test #111 yielded kerosene 2%, gas oil 6%, a loss of 1.4%; 2% of 77.4 sec. viscosity at 100°

35 F. 3 color, "nonvis neutral," and 2% of 166.1 viscosity at 100° F.; 4½ color neutral; test #112 yielded kerosene 4%, gas oil 10%, loss of 1.2%, 5.5% of 1½ color "nonvis neutral" and 8.5% of 40 2½ color "180 neutral." It will be observed that the gravity of the S. A. E. 20 motor oils in all these cases is lower than is customary from pure Pennsylvania crude, yet the viscosity characteristics and flash and fire points are very substantially better; the extremely high flash and fire points of the bright stock from test #112 are notable. These tests indicate both of the important refining improvements mentioned above.

Tests 110, 111, 112 were made with the idea of 50 making up a synthetic crude oil which was proportionally recombined where necessary and filtered, then it was vacuum distilled in the laboratory. In the case of #110, the transfer line was directly connected to the condenser, with no 55 steam being used. In the case of #111, 95% by volume of water was charged with the oil and clay, and the transfer line again connected directly to the condenser. In the case of #112, the oil and clay were charged to the heating coil while 60 95% by volume of water based on the oil and converted into steam was charged into the base of the tower, and the overhead led to a condenser, by-passing tower sections 1, 2, 3, and 4. When the level or column height of the liquid in the 65 reaction or flash chamber reached approximately 7 feet, the samples of overhead condensate and bottoms were proportionally combined and filtered to make the synthetic crude for laboratory evaluation.

70 In the accomplishment of any refining process, manufacturing and economic considerations virtually make mandatory continuous rather than batch operation, and this process is very satisfactory in continuous operation. Both acid-activated clay and the chemicals disclosed herein can

be made into a finely divided state suitable for mixing with oil and pumping through a pipe still. The essential difference between continuous operation in a pipe still and batch operation is that the whole volume of oil is subjected to the maximum temperature in pipe still operation, while in batch operation continuous evolution of volatile materials occurs as the temperature is raised beyond the point of initial volatility. Other variables, such as rate of charge, tube size, tube length, furnace exit temperature, etc., will occur to the minds of persons skilled in the art.

In the case of tests #110, #111 and #112 above, and in the tests which follow, the essential data with reference to the still used are: $\frac{1}{2}$ inch tubes, total length from the furnace inlet including that in heating zone and transfer line to the point of entrance to the reaction or flash chamber, 3138 inches, of which 2162 inches was in furnace heating zone, and 130 inches transfer line length between furnace outlet and reaction chamber. The transfer line discharged into a vertical reaction chamber made of 6" pipe at a point ten feet above the base, in which base was located the discharge line and the steam flashing line. Of course, the size and length of the reaction chamber may be varied to secure any desired time of contact, as may also the furnace constants and variables, or the level carried in the reaction chamber. If desired, the reaction chamber may be arranged for auxiliary heating, as indicated in the attached drawing preferably down draft from the furnace itself. If virtually complete volatilization of the oil from the reaction chamber is desired, the chamber may be arranged for the mechanical removal of the residual matter including clay and chemicals.

Separation of the overhead materials into components suitable for evaluation in the laboratory

was effected by passing the overhead in succession through a 6" x 12', a 6" x 12' and a 10" x 12' tower, each with about 10' 6" broken tile reflux surface and followed by a condenser and receiver, with suitable by-pass arrangements so that up to four separations could be made in the overhead. A branched connection from the transfer line directly to a combined cooler and condenser enabled by-passing the reaction chamber and all of the towers.

Runs or tests Nos. 110, 111, 112 were made for the purpose of determining the effect of steam on the reaction. In test #110 the transfer line was directly coupled to the condenser causing the oils to thereby by-pass the reaction chamber and towers, and the total run into a drum on a scale where the recovery was identical with the charge. No steam was used except that from the clay. The transfer line temperature was 845° F. Test #111 was made with by-passed reaction chamber and towers, with 845° F. transfer line temperature, using 95 parts by volume of water for each 100 parts by volume of oil which was charged under pressure into the oil and clay mixture through pipe 31 from an auxiliary pump (not shown). The oils under test #112 above were made with by-passed towers, furnace exit temperature of 845° F. approximately 7 feet oil level in reaction chamber, and close to 650° F. temperature in base of reaction chamber, with steam, approximately 95% by volume (condensed), or 105% by weight of the oil charged, into the base of the reaction chamber. The overhead and reaction chamber bottoms were proportionally recombined, filtered, vacuum distilled and tested.

The results of additional tests similar to the foregoing have been summarized in the following table, divided endwise into two sections which should be placed side by side to be read:

¹Impure.

In the above two section table "Bottoms" refers to the filtered oil recovered from the material extracted from the base of the reaction chamber; "Tower A overhead," to the material withdrawn from the cooler attached to the first overhead collection chamber; "Tower B overhead," to the material similarly withdrawn from the second overhead collection chamber; "Tower C overhead," to material from the third chamber; and "Condensate," to the material withdrawn from the condenser receiver. In some cases tower C was bypassed, in which case the proper notation was made. The difference between the "Furnace outlet temperature" and the "Reaction chamber base temperature," is the temperature range existing in the oil and clay being treated. "Steam, percent of oil charged" means volume of water in percent referred to the volume of the oil charged, changed into steam and fed into the base of the reaction chamber. The various test designations refer to those common in the industry. In test Q no flashing steam was used except that in the clay.

In an example of the operation of a unit in accordance with this invention, a mixture of acid activated clay and oil was charged through the heater and there heated to the desired temperature. This mixture was discharged into the reaction tower maintained at substantially atmospheric pressure. At the same time, steam from the steam generator, in a volume ratio relative to the oil charge, was introduced into the bottom of the reaction tower. The towers, previously, had been brought to the desired temperature by the injection of superheated steam. The charging of steam to the towers was continued until the unit was on stream. When the unit was on stream the steam at the bottoms of towers Nos. 2, 3, and 4 were, generally speaking, cut off, and the charge of oil, clay and steam in the reaction vessel was maintained at the desired

charge rate. During operation a liquid level of approximately 7' was maintained in the reaction tower, although this level was varied at different times.

The quantities of clay used per gallon of oil charged in these tests varied from $\frac{1}{2}$ pound to $1\frac{1}{4}$ pounds, but lesser and greater amounts can be used depending upon the oil treated and results desired. It was discovered that one pound was close to the optimum for this oil. The necessary quantity of clay required is less usually than 25% of the weight of the oil being treated. Clays from different sources or methods of preparation vary markedly in their effectiveness. The necessary quantity of a clay for any given oil is determined readily by experimentation, taking into consideration the quantity of vaporized material desired, quality and quantity of residual products desired, and temperature and time as well as other governing factors involved. Quite wide variation in results can be obtained with a given quantity of acid activated clay by varying time of contact and temperature. The transfer line temperature is regarded to be of primary importance, and soaking time and temperature of secondary importance. The transfer line temperatures varied from 800-879° F. insofar as the data herewith is concerned. The temperatures to be used must be determined experimentally for different oils and end results and are usually lower than the above range for naphthenic oils.

The catalyst used in the examples, for which data is given in the tables herein, consisted of "Super Filtral" (sulfuric acid activated clay). However, bauxite and hydrochloric acid activated clays were used, but it was found in the work with bauxite that this material has too high a specific gravity, to be readily pumped through a pipe still without continuous risk of clogging at some point in the apparatus and it was found necessary to use it in conjunction with "Super

Filtrol." Where bauxite was used with "Super Filtrol," this is indicated on the table. None of the work on the hydrochloric acid clays is reported in the tables included herein, this work having been done at an earlier time. The German "Tonsil" clay was found to be more effective than "Super Filtrol" on a dry basis. Work was also done with four samples of hydrochloric acid activated clays manufactured by an American company and normally used in the decolorization of fatty oils. In this work it was found that one of these clays which was least effective for the treatment of fatty oils was most effective from the standpoint of the process. This indicates that the greater efficiency of the "Tonsil" clay was traceable to the presence of impurities in the clay which serve to act as desulphurizing agents and thereby reduce the normal clay requirements of the reaction. In connection with this, it was observed that the clay requirements of the process can be materially reduced by incorporating in the reaction mixture a small proportion of any one of the large group of metallic compounds which form stable compounds with sulphur or other impurities. The quantity of desulphurizing metal used appears to be quite critical. This is particularly so in the case of copper, and the quantity used must be controlled within narrow limits in order to obtain maximum efficiency and effectiveness.

Synthetic crudes of these three tests were made, filtered and vacuum stills in the laboratory to yield the results shown on the tables included herein.

It might be mentioned here that for the purpose of separating spent catalyst from the oil, the mixture of oil and spent catalyst was filtered through a plate and frame filter press although any suitable method may be used.

A consideration of the results obtained indicates that two primary effects take place, namely, degradation and volatilization of unstable components, and a chemical alteration and increased stabilization of stable components, probably by a reaction such as cyclization or hydrogenation. Thus, among others, two important refining improvements result:

1. Products having both improved viscosity index and improved physical characteristics are produced.

2. The production of large quantities of light-bodied lubricants of high quality from less useful heavy-bodied oils becomes feasible, together with the production of residual heavy-bodied oils which have an extremely high quality.

Insofar as known, no other means of accomplishing these results are available. In making this statement, it is recognized that the results obtained by the hydrogenation of lubricating oils might be cited as a qualification.

The process is equally applicable to paraffin base, naphthene base, and mixed base oils. The effectiveness, when considered in the light of actual improvement, say, in viscosity index, is greater in the case of the naphthene base oils because there the chances of improving viscosity index are greater. In this connection, some of the work on straight zero viscosity index naphthene base oils resulted in a material with a viscosity index of about 40 to 44. On furfural refined naphthenic oil having an initial viscosity index of 63, a carbon residue of 0.09%, a sulphur of 0.22% and a No. 3 color, with a purplish bloom, the application of the process resulted in a product having a viscosity index of 78, a carbon

residue of 0.08%, a sulphur of 0.12% and a 1 1/4 color, with a yellow-green bloom. These tests do not represent the feasible upper limits obtainable with this improved process, but they indicate the practicability of the process.

The examples explained above lead one to conclude that the best possible oils for internal combustion engines can be made by means of the application of this process to naphthenic oils, because the low pour and low carbon tests are retained, while high viscosity index, high flash and stability not originally present are produced in the oil. The foregoing remarks are also applicable to mixed base oils which can be readily converted into high-grade products by the application of the process.

Residual oils resulting from the high temperature treatment of petroleum, petroleum products, or other hydrocarbon materials, usually have a foul, obnoxious odor, and are unstable. Treatment by the process herein disclosed eliminates most of these objectionable characteristics, but it was discovered that certain residual oils were not deodorized sufficiently by this means to be marketable, with economically feasible quantities of acid activated clay. Experimentation led to the discovery that certain impurities existing in hydrocarbon materials, probably forms of oxygen, sulfur, halogen, nitrogen, or other impurity, act as clay poisons, hence if a method could be devised for neutralizing or eliminating these products, marked economies in clay quantities required could be effected.

Investigation of the impurity problem using an Onondaga crude oil as the working agent, led to the discovery that certain metals, preferably in the form of compounds, including metallic salts, when used in connection with acid activated clay at temperatures substantially above 400° F. enabled the elimination of much of the undesirable matter from the residual oil, the undesired materials evolving with the distillate or being removed with the clay. In some cases temperatures above 740° F. were used. Among the impurities evolved with different metallic compounds or salts used in this connection were sulfur flowers, sulfur dioxide gas, hydrogen sulfide, ammonia gas, amines, nitrogen oxide, alcohols and quantities of unidentified, rank smelling, choking, gaseous materials and small amounts of unidentified white and pink-white solids. Further work with solvent refined oils led to the detection of odors of nitrobenzene, furfural and phenol in the vapors distilled off of various oils.

With reference to the common heavy metals usually in the form of oxides or salts, copper, zinc, nickel, and iron gave excellent color results in acid activated clay treatments of Onondaga crude oil; all of the heavy metals tested, including lead, manganese, and chromium as well as copper, nickel, zinc, and iron produced odor improvement. As a check on other oils, copper oxide was tried with excellent results on a wide variety of oils, both paraffinic, mixed base and asphaltic or so-called naphthenic oils, showing that the process is applicable generally, and permitting the choice of the metal best fitting the particular oil being investigated. In several cases, mixtures of metals were used effectively to secure the beneficial effects resulting from the combination.

Because of the wide choice of metal compounds and salts available, and the fact that materials remaining with the oil because of the treatment, such as halogen compounds, phosphorus com-

pounds, sulfur compounds, nitrogen compounds and oxygen compounds are known definitely to affect film strength and oiliness characteristics of lubricants, a wide variety of copper compounds was used with the clay on Onondaga crude oil to demonstrate the effect of varying the compound or salt used. Onondaga crude oil gives a negative chlorine indication by means of the commonly used flame test with hot copper wire, showing virtual absence of chlorine in the crude oil itself; when treated with cuprous chloride in connection with acid activated clay, among other substances, large amounts of hydrochloric acid gas were evolved, but the filtered residual oil still gave a negative chlorine test by means of the same copper wire flame test; when treated with cupric chloride, however, in addition to the large amounts of hydrochloric acid gas evolved, the filtered residual oil gave a positive chlorine test, indicating chlorine remaining in the oil; in neither of the latter cases were flowers of sulfur condensed in the condenser tube but a heavy yellow, oily substance condensing in the tube was noticed in both cases.

Copper sulfate used in a similar manner showed heavy flowers of sulfur deposits in the condenser tube, and heavy evolution of sulfur dioxide gas, as well as other impurities. With cupric acetate, acetic acid fumes without deposit of flowers of sulfur in the condenser tube were noted; with cupric phosphate the fume was led through water before examination, nevertheless heavy deposits of flowers of sulfur were noted in the condenser tube, and hydrogen sulfide was noticed in the fume bath; with cupric chromate, heavy flowers of sulfur deposits were noted in the condenser tube, together with heavy evolution of fumes, and a relatively clean appearing distillate; cupric hydroxide, cuprous oxide, cupric oxide, cupric carbonate, cupric hydroxide-carbonate, reactive copper silicate and cupric-nickelate hydroxide, each in combination with acid activated clay permitted evolution of flowers of sulfur and yielded satisfactory residual products. In connection with nitrates, nitrogen oxide as well as both ammonia gas and amines were detected among the impurities evolved. Combinations of metallic salts have been used and may be used if desired.

It is quite within the scope of this disclosure to use combinations either of metals, metals and salts, or salts of metals, in connection with acid activated clay or clays, depending upon results desired. Inclusion of a portion of the acidic radical in the residual oil also may decide the choice.

In preventing the poisoning of the clay by the impurities of the hydrocarbon under treatment, the metals in pure metallic subdivided form do not appear to be as satisfactory in action as are the compounds of the metals, and particularly the salts of the metals.

It will be understood that various changes in the details which have been herein described in order to explain the nature of the invention, may be made by those skilled in the art, within the principle and scope of the invention, as expressed in the appended claims.

I claim:

1. In the conversion of a naphthenic petroleum oil, to obtain a relatively high yield of light-bodied lubricating components of superior physical characteristics, such as a high viscosity index, high flash and stability, the improved method which comprises mixing said oil, while at a temperature below its natural cracking tem-

perature, with unspent, acid-activated clay to provide a pumpable mixture in which the clay is suspended in the oil and amounts to approximately between one-half pound and one and one-quarter pounds per gallon of oil, passing said mixture as a stream in liquid phase and upwardly through an ascending heating passage and then into a reaction chamber, incorporating water in the mixture before it completes its ascent in said passage equal to approximately 95 per cent of the oil, heating the mixture while moving in said passage approximately to cracking temperature below approximately 900 degrees F., flashing the heated mixture with a vapor in

10 said chamber at cracking temperature, separating the overhead vapors from the bottoms containing the clay, and condensing the overhead vapors.

2. In the conversion of a naphthenic petroleum oil, to obtain a relatively high yield of light-bodied lubricating components of superior physical characteristics, such as a high viscosity index, high flash and stability, the improved method which comprises mixing said oil, while at a

20 temperature below its natural cracking temperature, with unspent, acid-activated clay to provide a pumpable mixture in which the clay is suspended in the oil and amounts to approximately between one-half pound and one and one-quarter pounds per gallon of oil, passing said mixture as a stream in liquid phase and upwardly through an ascending heating passage and then into a reaction chamber, incorporating in the mixture before it completes its ascent in said

25 passage, a flashing agent in liquid phase which vaporizes at a temperature lower than that to which the mixture is heated before it reaches the top of said ascending passage, equal to approximately 95 per cent of the oil, heating the mixture while moving in said passage approximately to cracking temperature below approximately 900 degrees F., flashing the heated mixture with a vapor in said chamber at cracking temperature, separating the overhead vapors from the bottoms

30 containing the clay, and condensing the overhead vapors.

3. In the conversion of a naphthenic petroleum oil, to obtain a relatively high yield of light-bodied lubricating components of superior physical characteristics, such as a high viscosity index, high flash and stability, the improved method which comprises mixing said oil, while at a

35 temperature below its natural cracking temperature, with unspent, acid-activated clay and a finely divided agent containing a metal to provide a pumpable mixture in which the clay and finely divided agent are suspended in the oil an amount to approximately between one-half pound and one and one-quarter pounds per gallon of oil, passing said mixture as a stream in liquid phase and upwardly through an ascending heating passage, and then into a reaction chamber, incorporating water in the mixture before it completes its ascent in said passage equal

40 to approximately 95 per cent of the oil, heating the mixture while moving in said passage approximately to cracking temperature below approximately 900 degrees F., flashing the heated mixture with a vapor in said chamber at cracking temperature, separating the overhead vapors from the bottoms

45 containing the clay, and condensing the overhead vapors.

4. In the conversion of a petroleum oil, to obtain a relatively high yield of light-bodied lubri-

50 cation, with unspent, acid-activated clay and a finely divided agent containing a metal to provide a pumpable mixture in which the clay and finely divided agent are suspended in the oil an amount to approximately between one-half pound and one and one-quarter pounds per gallon of oil, passing said mixture as a stream in liquid phase and upwardly through an ascending heating passage, and then into a reaction chamber, incorporating water in the mixture before it completes its ascent in said passage equal

55 to approximately 95 per cent of the oil, heating the mixture while moving in said passage approximately to cracking temperature below approximately 900 degrees F., flashing the heated mixture with a vapor in said chamber at cracking temperature, separating the overhead vapors from the bottoms

60 containing the clay, and condensing the overhead vapors.

5. In the conversion of a petroleum oil, to obtain a relatively high yield of light-bodied lubri-

55 cation, with unspent, acid-activated clay and a finely divided agent containing a metal to provide a pumpable mixture in which the clay and finely divided agent are suspended in the oil an amount to approximately between one-half pound and one and one-quarter pounds per gallon of oil, passing said mixture as a stream in liquid phase and upwardly through an ascending heating passage, and then into a reaction chamber, incorporating water in the mixture before it completes its ascent in said passage equal

65 to approximately 95 per cent of the oil, heating the mixture while moving in said passage approximately to cracking temperature below approximately 900 degrees F., flashing the heated mixture with a vapor in said chamber at cracking temperature, separating the overhead vapors from the bottoms

70 containing the clay, and condensing the overhead vapors.

6. In the conversion of a petroleum oil, to obtain a relatively high yield of light-bodied lubri-

65 cation, with unspent, acid-activated clay and a finely divided agent containing a metal to provide a pumpable mixture in which the clay and finely divided agent are suspended in the oil an amount to approximately between one-half pound and one and one-quarter pounds per gallon of oil, passing said mixture as a stream in liquid phase and upwardly through an ascending heating passage, and then into a reaction chamber, incorporating water in the mixture before it completes its ascent in said passage equal

75 to approximately 95 per cent of the oil, heating the mixture while moving in said passage approximately to cracking temperature below approximately 900 degrees F., flashing the heated mixture with a vapor in said chamber at cracking temperature, separating the overhead vapors from the bottoms

80 containing the clay, and condensing the overhead vapors.

cating components with relatively high viscosity index, high flash and stability, the improved method which comprises mixing said oil while at a temperature below its natural cracking temperature with unspent, acid-activated clay, to provide a pumpable mixture in which the clay is suspended in the oil and amounts to at least approximately one-half pound of clay per gallon of oil, passing said mixture as a stream in liquid phase upwardly in an ascending heating passage, heating the stream in said passage to the desired conversion temperature and below approximately 900 degrees F., incorporating a readily volatilizable liquid in the mixture of said stream before the stream completes its ascent and before the temperature is raised to the maximum extent, flashing the heated mixture of said stream after it reaches said desired conversion temperature to create vapors, separating the vapors from the bottoms containing the clay, and condensing the vapors.

5. In the conversion of a naphthenic petroleum oil, to obtain a relatively high yield of light-bodied lubricating components with relatively high viscosity index, high flash and stability, the improved method which comprises mixing said oil, while at a temperature below its natural cracking temperature, with unspent, acid-activated clay to provide a pumpable mixture in which the clay is suspended in the oil and amounts to at least approximately one-half pound of clay for each gallon of oil, passing said mixture as a stream in liquid phase upwardly through an ascending passage and then into a reaction chamber, incorporating water in the mixture of said stream before the stream completes its ascent in said passage, heating the mixture moving in said passage approximately to a desired conversion temperature and below approximately 900 degrees F., flashing the heated mixture in said chamber to create vapors, separating the overhead vapors from the bottoms containing the clay, and condensing the overhead vapors.

6. In the conversion of a petroleum oil, to obtain a relatively high yield of light-bodied lubricating components having a relatively high viscosity index, high flash and stability, the improved method which comprises mixing said oil while at a temperature below its natural cracking temperature with unspent, acid-activated clay to provide a pumpable mixture in which the clay amounts to at least approximately one-half pound per gallon of oil, passing said mixture as a stream in liquid phase upwardly in a confined passage and then into a reaction chamber, incorporating in said stream before it completes its ascent in said passage a flashing agent in liquid phase, which vaporizes at a temperature below that to which the stream is heated before it completes its ascent in said passage, heating the mixture moving in said passage to a desired conversion temperature less than approximately 900 degrees F., flashing the heated mixture in said chamber to create vapors, separating said vapors from the bottoms containing the clay, and condensing the overhead vapors.

7. In the conversion of a petroleum oil, to obtain a relatively high yield of light-bodied lubricating components of superior physical characteristics, such as a high viscosity index, high flash and stability, the improved method which comprises mixing said oil, while at a temperature below its natural cracking temperature, with unspent, acid-activated clay to provide a

5 pumppable mixture in which the clay is suspended in the oil and amounts to approximately between one-half pound and one and one-quarter pounds per gallon of oil, passing said mixture as a stream in liquid phase and upwardly through an ascending heating passage and then into a reaction chamber, incorporating water in the mixture before it completes its ascent in said passage, heating the mixture while moving in said passage approximately to cracking temperature below approximately 900 degrees F., flashing the heated mixture in said chamber at cracking temperature, separating the overhead vapors from the bottoms containing the clay, and condensing the overhead vapors.

8. In the conversion of a petroleum oil, to obtain a relatively high yield of light-bodied lubricating components with relatively high viscosity index, high flash and stability, the improved method which comprises mixing said oil while at a temperature below its natural cracking temperature with unspent, acid-activated clay, to provide a pumpable mixture in which the clay is suspended in the oil, passing said mixture as a stream in liquid phase upwardly in an ascending heating passage, heating the stream in said passage to the desired conversion temperature and below approximately 900 degrees F., incorporating a readily volatilizable liquid in the mixture of said stream before the stream completes its ascent and before the temperature is raised to the maximum extent, flashing the heated mixture of said stream after it reaches said desired conversion temperature to create vapors, separating the vapors from the bottoms containing the clay, and condensing the vapors.

9. In the conversion of a naphthenic petroleum oil, to obtain a relatively high yield of light-bodied lubricating components with relatively high viscosity index, high flash and stability, the improved method which comprises mixing said oil, while at a temperature below its natural cracking temperature, with unspent, acid-activated clay to provide a pumpable mixture in which the clay is suspended in the oil, passing said mixture as a stream in liquid phase upwardly through an ascending passage and then into a reaction chamber, incorporating water in the mixture of said stream before the stream completes its ascent in said passage, heating the mixture moving in said passage approximately to a desired conversion temperature and below approximately 900 degrees F., flashing the heated mixture in said chamber to create vapors, separating the overhead vapors from the bottoms containing the clay, and condensing the overhead vapors.

10. In the conversion of a petroleum oil, to obtain a relatively high yield of light-bodied lubricating components with relatively high viscosity index, high flash and stability, the improved method which comprises mixing said oil while at a temperature below its natural cracking temperature with unspent, acid-activated clay and a metallic oxide, to provide a pumpable mixture in which the clay is suspended in the oil and amounts to at least approximately one-half pound of clay per gallon of oil, passing said mixture as a stream in liquid phase upwardly in an ascending heating passage, heating the stream in said passage to the desired conversion temperature and below approximately 900 degrees F., incorporating a readily volatilizable liquid in the mixture of said stream before the stream completes its ascent and before the temperature

is raised to the maximum extent, flashing the heated mixture of said stream after it reaches said desired conversion temperature to create vapors, separating the vapors from the bottoms containing the clay, and condensing the vapors.

11. In the conversion of a petroleum oil, to obtain a relatively high yield of light-bodied lubricating components of superior physical characteristics, such as a high viscosity index, high flash and stability, the improved method which comprises mixing said oil, while at a temperature below its natural cracking temperature, with unspent, acid-activated clay to provide a pumpable mixture in which the clay is suspended in the oil and amounts to approximately between one-half pound and one and one-quarter pounds per gallon of oil, passing said mixture as a stream in liquid phase and upwardly through an ascending heating passage and then into a reaction chamber, incorporating water in the mixture before it completes its ascent in said passage equal to approximately 95 per cent of the oil, heating the mixture while moving in said passage approximately to cracking temperature below approximately 900 degrees F., flashing the heated mixture with a vapor in said chamber at cracking temperature, separating the overhead vapors

from the bottoms containing the clay, and condensing the overhead vapors.

12. In the conversion of a petroleum oil, to obtain a relatively high yield of light-bodied lubricating components with relatively high viscosity index, high flash and stability, the improved method which comprises mixing said oil while at a temperature below its natural cracking temperature with unspent, acid-activated clay, to provide a pumpable mixture in which the clay is suspended in the oil, passing said mixture as a stream in liquid phase upwardly in a heating passage, heating the stream in said passage to the desired conversion temperature and below approximately 900 degrees F., incorporating a readily volatilizable liquid in the mixture of said stream before the stream completes its ascent and before the temperature is raised to the maximum extent, flashing the heated mixture of said stream with steam in an amount which before conversion from water to steam was at least 75 percent by volume of the oil, after it reaches said desired conversion temperature to create vapors, separating the vapors from the bottoms containing the clay, and condensing the vapors.

WILLIAM ALVAH SMITH.
